UNITED STATES PATENT OFFICE.

EDWARD M. MORAN, OF BERKELEY, CALIFORNIA.

DIAPHRAGM AND METHOD OF MAKING SAME.

Application filed April 21, 1920. Serial No. 375,586.

To all whom it may concern:

Be it known that I, EDWARD M. MORAN, a citizen of the United States, residing at Berkeley, in the county of Alameda and State of California, have invented a new and useful Improvement in Diaphragms and Methods of Making Same, of which the following is a specification.

This invention relates to a meter diaphragm and an apparatus for making the same.

Heretofore it has been common practice to form meter diaphragms, especially for use with gas meters from strips of leather which have been gathered along their opposite edges and secured to mounting rings, said strips being united at the joint of their contiguous edges in a manner to prevent leakage of the gas. Due to this arrangement the exact volume of the diaphragm cannot be always ascertained and furthermore, the diaphragm is liable to leak even through every precaution is exercised in its formation.

It is the principal object of the present invention to provide a meter diaphragm which is formed from a single seamless piece of leather and which may be made of any desired shape and furthermore without requiring tucking or sewing operations, said diaphragm being shaped upon a collapsible form.

The present invention is illustrated by way of example in the accompanying drawings, in which:

Fig. 1 is a view in plane illustrating the form upon which the diaphragms are made.

Fig. 2 is a view in transverse section through the form as shown in Fig. 1.

Fig. 3 is a view in section and elevation showing the position of the diaphragm upon the form.

Fig. 4 is a view in perspective illustrating the completely formed diaphragm.

In the drawings, 10 indicates a collapsible form upon which a diaphragm 11 is made. The form is clearly shown in Figs. 1 and 2 where it will be seen to comprise a bottom member 12 and an annular collapsible member 13. The bottom member 12 may be of any desired configuration and is preferably made from light sheet metal to provide an outer wall 14 and an inner wall 15. The wall 15 is substantially circular and is formed with an annular flange 16 adjacent its marginal edge to receive the

lower portion of the collapsible form. The collapsible form is also made from light gauge sheet metal and comprises arcuate form segments 17, 18 and 19 and 20. The segments 18 and 20 are hinged to the opposite ends of the segments 17 by means of hinge members 21. The joints of segments 17, 18 and 20 are along lines radial with the center of the form. The segment 19 is adapted to be completely removed from its position between the opposite ends of segments 18 and 20, the joints in this case being parallel to a line passing through the center of the form and across the middle of the segment 19. This segment is secured in position by clamping nuts 22 which engage screw studs 23 extending radially from the inner faces of the segments 18 and 20 and adjacent the form segment 19. The screws 23 are adapted to pass through openings in a fastening plate 24 secured to the inner face of the segment 19. It will therefore be evident that when the segment is in position and held by the nuts 22 it will hold the segments 17, 18 and 20 in rigid relation to each other and will combine therewith to provide an annular form. The outer contour of this form may be as desired although in the present instance is shown as having an arcuate face 25 as clearly disclosed in Fig. 2. A straight circumferential lip 26 is formed as a continuation of this face on one side, while the outer contour of the bottom plate 14 is adapted to blend into the lines of the arcuate face 25. It is also to be understood that the bottom member 12 might be eliminated if desired or that bottom members or other configuration might be used without departing from the spirit of this invention.

A combined locking and centering means is provided to secure the bottom member in relation to the annular form and to produce a rigid structure. This comprises a tubular stem 27 which is rigidly secured to the bottom of the form at its center and projects from the face 15. This stem is adapted to receive a center pin 28 which may be secured in position by a set screw 29. The center pin carries a rigid rod 30, the outer ends of which are formed with locking fins 31 which pass into a slot between members 32 carried by the form segments 18 and 20. This slot is slightly inclined to the horizontal so that movement of the rod 30 to bring the fins to a seat will act

to bind the bottom 12 and the annular form 13 together in a rigid manner.

In operation of this invention to produce a diaphragm of the character described, a circular sheet of leather is dampened and thereafter the assembled form is brought to rest thereon. The leather is then gradually stretched and worked around the sides of the form so that the outer edge of the leather may be brought around the cylindrical lip portion 26, after which an elastic band 33 is placed around the leather to temporarily hold it and to permit further stretching and working of the leather to bring it to conform to the exact contour of the form. The leather may then be permitted to dry and when in proper condition segment 19 of the form may be removed. The set screw 29 may also be withdrawn to permit removal of the lock bar 30 after which the annular form may be collapsed and removed from the interior of the leather without distorting it. The bottom form 12 may also be removed after it has been separated from the annular form. The leather may then be treated as desired and used in the construction of a gas meter. It will be readily seen that by producing a meter diaphragm in the manner described, the leather will be caused to exactly assume the formation desired and accommodate a predetermined volume of gas. It will also be evident that no seams will exist in the leather and that it will be devoid of tucks thus making it possible to quickly secure it to the metal fittings usually provided.

While I have shown the preferred form of my invention as now known to me, it will be understood that various changes in the construction, combination and arrangement of parts may be made by those skilled in the art without departing from the spirit of the invention as claimed.

Having thus described my invention, what I claim and desire to secure by Letters Patent, is:

1. A device to form flexible meter diaphragms, comprising a base member, and an arcuate sectional, collapsible form adapted to be connected to the base and over which form a flexible meter diaphragm may be moulded.

2. A device to form flexible meter diaphragms, the said device comprising a base member having a rim, and circular segments having an exterior curvature over which a diaphragm may be moulded, the said segments collapsibly united and adapted to be secured to the base.

3. A diaphragm moulding form comprising sectional segments having an exterior curvature over which the diaphragm is to be formed, foldable joints uniting contiguous segments, a removable, completing

segment, and intermediate bracing means to retain the structure sections.

4. A flexible diaphragm forming device, comprising a base with an upwardly curving rim, arcuate segmental sections collapsibly united together, with their lower edges forming a curved continuation of the rim, and with a cylindrical extension of the upper edge of the segments and means to unite and center the structural members.

5. A flexible diaphragm forming device, including a base with an upwardly and outwardly curved rim, arcuate segmental sections collapsibly united and having their lower edges forming a curved continuation of the rim, and having a cylindrical extension of the upper edge of the segments, and means to unite the structural members consisting of a socket tube and an adjustable stem extending upwardly from the base and a transverse bar extending across the stem with latching means uniting its ends with the segmental sections.

6. A single piece diaphragm forming apparatus, including curved collapsible segments with means uniting the segments into a continuous structure, and a uniting and retaining intermediate mechanism, a cylindrical band receiving extension over which the diaphragm is extended from the shaping segments and retained, and a band to fit over said band receiving extension to retain the diaphragm against the extension.

7. A diaphragm forming device comprising sectional segments, each having an exterior curvature offset from one edge of the respective segments so as to provide an annular member having a curved portion over which the diaphragm is formed and an annular extension between the curved portion and the adjacent edge of said member, and means to embrace said extension and hold the diaphragm against the extension.

8. A diaphragm forming device comprising sectional segments, each having an exterior curvature offset from one edge of the respective segments so as to provide an annular member having a curved portion over which the diaphragm is formed and an annular extension between the curved portion and the adjacent edge of said member, means to embrace said extension and hold the diaphragm against the extension, and means confined within the device to retain the segments in the aforesaid annular formation.

In testimony whereof I have hereunto set my hand in the presence of two subscribing witnesses.

EDWARD M. MORAN.
